UNITED STATES PATENT OFFICE.

JOHN H. MACALMAN, OF SOMERVILLE, MASSACHUSETTS.

DESIGN FOR A VEHICLE-BODY.

SPECIFICATION forming part of Design No. 35,909, dated May 13, 1902.

Application filed February 12, 1902. Serial No. 93,804. Term of patent 7 years.

To all whom it may concern:

Be it known that I, JOHN H. MACALMAN, a citizen of the United States, residing at Somerville, in the county of Middlesex and State 5 of Massachusetts, have invented and produced a new and original Design for a Vehicle-Body, of which the following description, in connection with the accompanying drawing, is a specification, like letters on the drawing representing like parts.

The drawing in side elevation illustrates my invention.

As shown in the drawing, the leading and material feature of my design consists of a 15 dasher-box shaped as shown to present substantially vertical front and rear lines *h i*. The vertical front line *h* at its lower end meets a rearwardly and downwardly extended slightly-concave line *k*, which intersects 20 the bottom line *h'* of the body. The rear vertical line *i* terminates in a sweep or curve *i'*,

that blends into and meets the rear portion of the body. At the top of the box the front and rear vertical lines *h i* are connected by a forwardly and upwardly inclined slightly-concave top line *j*, which meets the front vertical line in an apex *j'* and the rear vertical line *i* in a curve or sweep *j''*. 25

The rear of the body carrying the dasher-box described is shown in dotted lines. 30

Having described my invention, what I claim as new, and desire to secure by Letters Patent, is—

The design for vehicle-body herein described and shown. 35

In testimony whereof I have signed my name to this specification in the presence of two subscribing witnesses.

JOHN H. MACALMAN.

Witnesses:
